UNITED STATES PATENT OFFICE

HARRY F. SMITH, OF DAYTON, OHIO, ASSIGNOR TO THE GAS RESEARCH COMPANY, OF DAYTON, OHIO, A CORPORATION OF OHIO

GAS PRODUCER

Application filed November 17, 1921. Serial No. 515,861.

This invention relates to gas generation, and more particularly to the generation of producer gas.

One of the principal objects of the invention is to provide an improved method of gas generation, and apparatus for carrying that method into effect, in which the time of the blowing up period is materially shortened, the character of the generated gas is improved and maintained more uniform, and the expense of operating and maintaining the apparatus materially decreased.

Another object of the invention is to provide a gas producer in which part of the fuel within the generating chamber functions as a lining for that chamber.

Another object is to provide an improved form of saturator.

Still another object is to provide a combined purifier and saturator.

Other objects and advantages of the invention will be apparent from the description set out below when taken in connection with the accompanying drawing.

It is the very general practice in the gas producer art to provide the generating chamber of the gas producer with a heat resisting and heat insulating lining, which serves to both cut down radiation losses from the active fuel bed and to prevent the metallic shell of the producer from being unduly heated. This lining usually consists of firebrick, the lining ordinarily varying in thickness, in the producers in general use, from six to twelve inches. Sometimes the fire brick lining is dispensed with and a water cooled shell for the generating chamber provided. In producers, as heretofore used commercially, which generally run from three to fourteen feet in internal diameter, the ratio between the mass of incandescent fuel within the active fuel bed, and the radiating surface of the producer shell is such that, with a lining of the kind specified, the heat losses, due to radiation, are comparatively so small that they occasion no serious trouble in the operation of the producer.

The initial blasting or starting period, though of considerable duration, perhaps as much as one-half to three-quarters of an hour,

or even more, is not objectionable since the producer is ordinarily brought up to good gas making conditions before there is any appreciable demand for the generated gas. And the heat losses during operation of the producer are not sufficient to seriously interfere with the gas making reactions. Still this heat loss does affect the efficiency of the gas making reactions, and in addition affects the quality of gas produced. For the higher the heat losses the greater will generally be the percentage of noncombustible within the generated gas. Therefore, any decrease in the relative proportion of heat loss by radiation results in a corresponding increase in efficiency of the apparatus.

While the radiation losses in producers of the kind heretofore generally used may be disregarded, when it is attempted to generate gas in producers of comparatively small size, for example those having a grate diameter of twelve inches, or less, it is found that the percentage of heat thus lost through radiation, tends to increase very rapidly as the diameter of the producer decreases. And if a producer of this small size is provided with a fire brick lining of a thickness corresponding, proportionately, to the thickness of the firebrick lining used in the conventional producer the heat losses will be so great that not only is the blowing up period unduly prolonged, but satisfactory operation of the producer is prevented. Increasing the thickness of the lining, to increase its resistance to transfer of heat therethrough, will cut down the radiation loss, and by providing a suitably thick lining the producer will function satisfactorily to make gas. However, if a firebrick lining of sufficient thickness to cut down radiation losses to a satisfactory degree is provided the heat capacity of this lining is so great that the blowing up period will be unduly prolonged. But such a small size producer will function satisfactorily if it is provided with a lining having sufficient heat insulating capabilities and also having small heat capacity.

A type of producer having a lining of this character is shown in the copending application of Harry F. Smith Serial No. 398,749

filed July 24, 1920. The producer disclosed in that copending application has a lining consisting of a thin inner layer of fire brick, of small heat capacity, backed by a comparatively thick layer of heat insulating material. Such a producer, with a grate of less than six inches diameter, operating upon charcoal, and starting cold, can be brought up to good gas making condition within fifteen minutes, and often in five minutes. But where the gas generated is to operate a gas engine, such an engine as forms the power unit of commercially well-known individual house lighting plants, it is especially desirable that the initial blasting or starting period be very brief, and that the producer quickly come up to approximately maximum gas making conditions. For the mixing valve, or carbureting device, which controls the air and gas mixture fed to the engine cannot be set for most efficient operation until the gas becomes of approximately uniform character.

In the producer illustrated in the drawing the initial blasting or starting period is so materially decreased, and the gas making reactions so controlled, that the producer is brought up to approximately maximum gas making conditions within a very short period, a period ordinarily not in excess of five minutes. This producer has no lining of the usual sort, but instead a part of the carbonaceous material which constitutes the fuel bed within the generating chamber thereof functions as a lining. With a producer of this character, having a grate diameter of four inches, and starting from cold, combustible gas has been secured in less than a minute, and a gas engine operated at substantially full load upon this gas within less than a minute and a half, from the time of first applying a match to ignite the fuel bed. Reference should be made to the copending application of Harry F. Smith, Serial Number 469,976, filed May 16, 1921, in which this type of construction is disclosed broadly, this present application disclosing specific and preferred embodiments of producer construction in accordance with the broad disclosure of this referred to copending application.

While this type of producer construction is especially valuable in connection with producers of very small size, it is also quite valuable in connection with larger size producers. But as illustrating a preferred embodiment, and for purposes of description, the invention is shown in connection with small size producers, such as would be used for operating a conventional house lighting plant, or for other domestic uses, such as cooking, heating, etc.

In the drawing in which like characters of reference designate like parts throughout the several views thereof,

Fig. 1 is a vertical sectional view through

a form of gas generating system embodying this invention, comprising as one element thereof a gas producer in which a part of the fuel bed functions as a lining, or to heat insulate the active zone of the fuel bed;

Fig. 2 is a vertical sectional view of the producer proper forming a part of Fig. 1, the view being in a plane at 90° from the plane of Fig. 1;

Fig. 3 is a view in elevation of the producer shown in Figs. 1 and 2;

Fig. 4 is a plan view of a somewhat modified form of gas generating system;

Fig. 5 is a view along the line 5—5 of Fig. 4;

Fig. 6 shows, in vertical section, still another modified form of generating system;

Fig. 7 is a plan view of the base member forming a part of the producer proper shown in Fig. 6;

Fig. 8 is a detail view, in section, along the line 8—8 of Fig. 7;

Fig. 9 is a vertical sectional view through a base member, similar to that shown in Figs. 1, 3 and 4, but in which a different type of grate, for supporting the fuel bed, is provided, this section being along the line 9—9 of Fig. 10;

Fig. 10 is a sectional view of the base member and grate shown in Fig. 9, the section being along the line 10—10 of Fig. 9;

Fig. 11 is a plan view of the purifier for the generated gas shown in Fig. 6;

Fig. 12 is a detail sectional view along the line 12—12 of Fig. 7, showing the air inlet into the saturator;

Fig. 13 is a detail sectional view along the line 13—13 of Fig. 7, showing the passage connecting the saturator to the ash pit;

Fig. 14 is a vertical sectional view of a fuel feeding mechanism constructed to be interchangeable with the closure member shown in several other views, such as Figs. 1, 5 and 6;

Fig. 15 is a detail sectional view of the operating handle of the fuel feeding mechanism, along line 15—15 of Fig. 14;

Fig. 16 is a detail plan view of one of the members carrying the locking lugs for holding the closing member or fuel feeding members in assembled position; and

Fig. 17 is a vertical sectional view of a modified form of producer, provided with a modified form of lining.

The producer, forming a part of the gas generating system shown in Fig. 1, which is designated generally by the numeral 20 comprises a metallic shell 21 and a base portion or member 22. The metallic shell 21 is preferably of sheet metal, the thickness of which varies according to the size of the producer. But inasmuch as this shell, in the modification shown, has to sustain little weight, other than the weight of the shell itself, it may be made of comparatively light material. In producers of the small size mentioned above,

- a shell made of one-sixteenth inch sheet steel has been found to function very satisfactorily. The upper end of the shell is closed by means of a top 23, which may be welded or otherwise secured in place, this top having an opening 24 therein, through which fuel is introduced into the generating chamber, this opening being surrounded by an upstanding flange 25. Cooperating with the flange 25 is
- 10 a cover 26, with which cooperates a clamp or bail 27. In the construction shown the cover 26 is substantially hemispherical in shape, and a correspondingly shaped bail is provided the ends of which are bent to form loops
- 15 or eyes which engage over suitable lugs carried by the members 28, which are in turn secured to the top 23, by any suitable means, such for instance as the bolts 29. The bail when positioned on the lugs is thus capable of
- 20 free movement into, or out of, engagement with the cover 26, to hold that cover in gas tight contact with the flange 25. A stop 30, is carried by the cover 26, to limit movement of the bail. The cover is provided with a
- 25 machined surface which is constructed to make a tight joint with the flange 25, when the cover is in place. If desired the cover may have a groove therein for receiving the flange 25, suitable packing being provided in
- 30 this groove to make a tight joint.
- The other end of the metallic shell 21 is open, and has an outstanding flange 32 there-around adapted to cooperate with the corresponding portion 33 of the base member 22.
- 35 A suitable packing member 34, preferably mounted within a groove 35, within the member 33, is provided so that when the shell and base members are drawn tightly together leakage between these two members is prevented.
- 40 Suitable eye members 36, are attached to the lower part of the shell with which cooperate hooks 37. Each of these hooks has its straight end threaded, and the base member is provided with passages
- 45 through which the various hook members extend when the apparatus is in assembled position. A plurality of legs 38, for supporting the base member and the shell, are provided, each of these legs having an internally threaded socket in the upper end thereof adapted to receive the threaded end of one of the hook members. In assembling the device the packing member 34 is first placed in position
- 50 within its groove 35 after which the shell is set thereon, the hook members positioned within the openings in the base 22, with the hooks engaged in the eye members 36, and the legs then rotated to draw the shell
- 55 and base member tightly together. An upstanding flange 39 is provided upon the base member, which extends a short distance upwardly into the shell member when the device is in assembled position, to hold the shell member and base member against lateral
- movement relative to each other, and the shell thus properly centered.
- The base member 22, when the device is assembled, and in operation, sustains the fuel bed, which is contained within the shell 21.
- 60 This base member is provided, centrally, with an opening 40, within which is positioned a ring 41 of heat resisting and heat insulating material, such material for instance as fire brick, carborundum, or the like. The ring 41 has a tuyère or opening 42 therein beneath which sets the grate 43, positioned within the ash pit 44, provided within the base member. The opening 42 serves as a blast port, or tuyère, opening into the gas generating
- 65 chamber, the grate 43, positioned beneath this opening, serving to sustain the greater part of the active or ignited portion of the fuel bed. The grate, in the modification shown, consists of a perforated disc supported upon three legs 46, one of which is extended to serve as a handle for moving the grate into and out of position. By this construction transfer of heat from the active zone of the fuel, through the grate, into the base member
- 70 is almost entirely prevented and heat losses from the fuel bed into the surrounding atmosphere, minimized. Because of the wide temperature range to which the ring 41 is subjected during operation it is of less diameter than the hole 40 to permit free contraction and expansion thereof, and suitable packing material 47, such as asbestos or the like, is provided to prevent leakage around the ring and through the hole 40, despite such
- 75 expansion or contraction. The ring 41 is also adapted to cut down heat transfer from the active zone of fuel to the base member, the asbestos packing 47 serving to augment the insulating effect of the ring. The opening into the ash pit is provided with a door 50, pivotally hinged at 51, the door being mounted in an inclined position, the construction being such that the door whenever released
- 80 will tend to fall into closed position.
- 85 Opening into the ash pit is a blast inlet 60, through which air and moisture pass into the ash pit and thence upwardly through the grate and tuyère 42 into the fuel bed where the gas making reactions occur. The generating chamber is provided with a central draft tube 65, connected through the pipe
- 90 66, lying within the generator shell, to the offtake passage 67, located within the base member, to which passage in turn is connected the gas offtake pipe 68.
- 95 The producer may be either suction or pressure operated. If pressure operated the blast will be forced through the opening 60 under pressure. As illustrated the producer is suction operated, a pump or exhauster 70, driven from any suitable power source, by means of the pulley and belt construction 71, being mounted within the delivery main 72
- 100 which is operatively connected to the offtake

pipe 68, the purifier 80 for the generated gas being interposed in the line connecting the exhauster 70 to the offtake passage 67. Or the producer may be connected to an internal combustion engine, furnishing gas for operating the engine, the engine in turn furnishing the suction for operating the producer.

The purifier, as illustrated, serves both to remove impurities such as dust, tar, and the like, from the generated gas and also as a vaporizer or saturator for furnishing moisture in the blast. It comprises a housing or bottom portion 81 and a double walled top 82 therefor, the bottom portion and top having cooperating flanges between which is mounted suitable packing 83 for preventing leakage between the two members when the device is in assembled position. Bolted or riveted to the bottom member 81 are a plurality of angle members 84, each of which has mounted, in a hole therein, a hook member 85, a spring surrounding the lower end of each hook member, one end of each spring bearing against one of the angles 84 and the other end against a pin or disc 86, carried by the hook members. The upper end of each of the hook members is shaped to cooperate with the flange of the top member 82 to hold that member tightly against the packing 83 and cooperating flange on the member 81. Ready access to the interior of the purifier is thus permitted while, at the same time, the top and bottom members of the purifier are held in gas tight contact with each other. Attached to the bottom wall of the top 82, and depending therefrom within the purifier, is an inverted bell shaped member 90, this member being spaced from the top 82, and connected thereto in any suitable fashion. As shown the two members are riveted together, suitable spacing rings 91 being provided for holding them in properly spaced position. Passing through the wall of the member 81, and terminating beneath the bell shaped member 90, is a section 92 of the gas delivery main 72. Attached to the end of this section 92, within the purifier is a fitting 93, the upper end 94 of which is cone shaped. Located within the purifier is a pan 95, the bottom of which has an opening therein surrounded by an upstanding flange 96, which is conical shaped to cooperate with the conical member 94. When the device is in assembled position the conical shaped member 94 is positioned within the conical flange 96 to sustain the pan in place. Positioned within the pan 95 is an inverted cup shaped member 100, the free edge of which seats upon the bottom of the pan 95 and is rigidly attached thereto, preferably in gas tight connection, the attachment in the construction shown being formed by welding the two members together. Supporting legs 101 are also provided, these legs being welded at opposite ends to the pan 95 and the member 100. The member 100 has a plurality of holes or perforations 102 therein, a finely perforated plate or layer of wire screen 103 being positioned over these holes and held in position by some suitable means, preferably spot welding. This screen should be of some material which will stand exposure to producer gas, a screen of Monel metal serving very well, though other material may be used as desired. A layer of fabric 104, such as a fabric for instance as flannel, is positioned on top of the screen 103, this fabric serving to retain the finely divided purifying material in place and being held in position by the spring 105, which may be of any desired construction. The upstanding wall 106 of the member 95 and the depending wall 107 of the member 100 are spaced a substantial distance apart, the depth of the pan 95 being greater than the depth of the member 100. This pan 95, during operation of the device, contains a finely divided or pulverized material 110 such as charcoal dust, preferably so finely divided that all of it will pass through a sixty mesh screen, arranged to form a layer of substantially uniform thickness over the member 100, and filling the trough which exists between the upstanding flange 106 and the depending flange 107. The offtake pipe 68 opens through the wall of the member 81, as shown in the dotted lines in Fig. 1, the construction of the purifier being such that gas from the producer passes through the pipe 68 into the purifier between the wall of the member 81 and the inverted cup shaped member 90. The gas passes over the member 90, between that member and the member 81, then upwardly between the member 90 and the upstanding flange 106, through the layer of purifying material, and out through the pipe 92 to the delivery main. As it passes through the material 110 the impurities such as dust, tar, etc., are removed therefrom. In practice it has been found that the pulverized material 110 tends, as a result of vibration to draw away from the flange 106. As a result unless means is provided for preventing it, some of the gas will be short circuited and will pass down through the space thus formed and through the cloth, screen, and perforated plate, without passing through the purifying material. In order to overcome this defect the trough or passage is provided between the flanges 104 and 106, which when filled with charcoal dust prevents the formation of these passages through which the gas may pass without being treated.

As stated above, the top 82 is double walled, a space 115 being provided between these two walls which, during operation of the device, contains a layer of water for providing moisture within the blast. As the hot gas from the offtake pipe 68 passes into the purifier it heats

the lower wall of the top 82, this heat being transmitted into the water within the space, or vaporizer, 115 to vaporize some of that water. Air for the producer blast passes in through the opening 116, in the upstanding flange 117, thence through the opening 118, in the top wall of the member 82, over the surface of the water within the vaporizer and thence through the inlet pipe 119 to the blast inlet 60. The level of the water within the vaporizer is maintained constant by means of an arrangement somewhat similar to the well known "chicken feed" apparatus, and for purposes of description this term is used to designate this particular part of the apparatus. This chicken feed regulator consists of an inverted vessel or glass bottle 120, the open mouth or neck 121 of which extends through the opening 118, into the vaporizer 20 and is supported by a spider 122. This bottle, at the beginning of operations, is filled with water and placed in inverted position. So long as the level of the water within the space 115 is sufficiently high to prevent the inflow of air to the bottle there will be no escape of water therefrom, but as soon as the level of water within the vaporizer falls sufficiently to uncover the mouth of the bottle water will flow therefrom into the vaporizer and air will 30 flow into the bottle to take its place. An automatic feed is thus provided to maintain the water level within the space 115 substantially constant. The bottle 120 is preferably of glass so that the quantity of water therein 35 may be easily seen, and a reserve water supply thus maintained. Flanges or baffles 124 are positioned within the vaporizer so that air passing through the vaporizer chamber from the inlet 116 to the outlet 130 is caused to flow over the whole surface of the water.

Apparatus of the character just described is termed a "saturator" and is operated on the principle that air in the presence of sufficient water vapor will become saturated at the temperature which exists. As the quantity of gas varies under varying load, or the offtake temperature of the gas varies, the heat input into the water in the vaporizer correspondingly varies and, therefore, the temperature 45 to which the air passing through the vaporizer is raised will also correspondingly vary. When more gas is being generated, therefore, the heat input into the vaporizer is greater to maintain a substantially constant saturation of the air even though more air is being passed through the saturator. And the reverse is true when the load for the producer falls off. Also if the offtake temperature of the gas tends to rise, or fall, which betokens 50 variable conditions within the active zone of the fuel bed, the heat input into the water in the vaporizer will correspondingly vary to vary the proportion of moisture in the blast to thus return conditions within the fuel bed 65 to normal.

The material 110 within the purifier, will normally have a long life during operation, but this material should be renewed from time to time. The spring hooks 85 for holding the members 81 and 82 in assembled position are provided in order that ready access may be had to the interior of the purifier for renewing this purifying material. To further facilitate ready access to the interior of the purifier the pipe connecting the space 115 to the blast inlet 60 is so constructed that it also may be readily detached from the member 82. As shown the top wall of the member 82 has an upstanding flange 130 which is provided with a seat 131. The pipe 119 has a 70 housing 132, in axial alignment with the flange 130 attached thereto. Slidably mounted within this housing 132 is a hollow plug 133, the lower end of which is adapted to cooperate with the seat 131, the interior of the plug within the housing being connected to the pipe 119 by means of a suitably arranged passage. A spring 134 is associated with the plug 133 and normally urges that plug into extended position, and, when the housing is 75 properly positioned, holds that plug tightly against the seat 131. The pipe 119 is so constructed that the housing 132 may be swung clear of the top 82 to permit ready removal of that top or swung back into alignment 80 with the flange 130 to connect the pipe 119 to the space 115. If desired a suitable swivel joint can be provided in the pipe 119 but satisfactory operation may be secured without such a joint. It has been found in practice, that suitable swinging movement of the member 132 may be secured by turning the threaded end 135, of the pipe 119, within the 85 cooperating internally threaded end of the passage 60.

As shown and described the producer has no definitely formed lining, such as has been utilized heretofore. Instead the unlined shell of the producer, is charged with fuel, the construction being such that only the central portion of this fuel bed is ignited, to constitute the active or generating zone, the passage of the blast through the ignited portion of the fuel bed being so controlled that a zone of inactive fuel, of suitable thickness, exists at all times, surrounding the active portion of the fuel bed and separating this active portion from the shell, to heat insulate the ignited fuel, this inactive portion or zone of the fuel bed thus functioning as a lining. The 90 passage of the blast through the fuel bed is readily controlled, within desired limits, by properly positioning and proportioning the offtake member 65 relative to the tuyère 42, and the diameter of the tuyère relative to the 95 diameter of the generating chamber. By increasing or decreasing the distance of this member from the tuyère the quantity of the ignited fuel i. e., the extent of the active zone, may be readily increased or decreased. With 100 105 110 115 120 125 130

any predetermined proportioning and positioning of the draft tube and the tuyère opening there will be a possible maximum extent of the active zone of the fuel bed under maximum load, which means when the maximum blast is passing through the fuel bed. As the load falls off the quantity of blast will correspondingly fall off and the extent of the active zone likewise decrease. Therefore, not only is there such control of the blast as will restrict the extent of the active fuel bed, but for any given construction there is a limitation of the maximum extent of that fuel bed.

In Figs. 4 and 5 is shown a somewhat modified form of construction. The producer proper, 20' is substantially identical with the producer shown in Figs. 1, 2 and 3 and described above. It varies primarily in that the passage 66' connecting the central draft tube 65' to the offtake pipe 68' passes directly through the side of the producer, instead of passing downwardly and connecting to a passage in the base member, which passage is in turn connected to the offtake pipe 68'. It is sometimes found, in the operation of the apparatus disclosed in Figs. 1 and 2, that the gas as it passes from the producer is cooled down so materially that sufficient heat is not present therein to cause the generation of suitable quantities of vapor in the vaporizing chamber 115 of the saturator. By passing the gas directly through the side of the producer to the offtake pipe 68', it is at a higher temperature as it passes to the saturator than is the case in the construction described above.

Where the gas is thus passed off directly through the side of the producer, the type of purifier and saturator shown in Fig. 1 may be utilized if desired. But other types of combined purifier and saturator may be used, another very satisfactory type being shown in Figs. 4 and 5, which type is fundamentally the same in principle and operation as the form of purifier described above.

This purifier and vaporizer comprises a cylindrical shell 150. While the shell in the purifier shown in Fig. 1 is also cylindrical, that shell is more in the nature of a pan, in that it has substantially greater diameter than height. But the shell 150 has substantially greater height than diameter. This shell has a top member 151, provided with a groove 152, adapted to receive the upper edge of the shell 150, suitable packing material 153 being provided for making a tight joint. The gas to be cleaned passes into the shell through the pipe 68' and out through the pipe 92', which in reality forms a section of the delivery main 72'. As in the construction described above a layer of filtering material is interposed between the inlet and the outlet pipes; but in this particular modification the construction is such as to facilitate and make particularly easy the removal of the filtering material. The

inner end of the outlet pipe is conical shaped as shown at 154, this conical shaped end being constructed to cooperate with a conical shaped opening 155 in the base member 156. Supported upon this base member is a frusto-conical member 157, which is perforated and which corresponds in function with the perforated member 103 in the purifier described above;—that is, it serves to support the filtering material. As shown the member 157 is constructed of suitable wire screen or cloth, but it may be of any other desired construction. A perforated sheet of steel functions very satisfactorily, and if desired this member, and the member 156 may be made of a single casting, although the construction shown has been found to function very satisfactorily indeed. The member 156 has a clamping flange 158 cooperating therewith, which serves to clamp to that member a hollow member 159 which is of a shape corresponding to the member 157, and which is spaced, when in assembled position, a suitable distance from said member. If desired the upper end of this member 159 may be left open, as shown, its lower end being also open and firmly held between the base member 156 and the flange 158. The member 159 is preferably made of wire cloth or screen, the size of the openings therein being dependent upon the sizing of the purifying material. Satisfactory operation has been attained with purifying material all of which passed over a 60 mesh screen the member 159, being made of 40 mesh screen. Of course the member 159 should be such that the purifying material will be retained therein, and in actual practice this occurs when the above dimensions are present. If desired this member may be of perforated sheet metal, or a casting, a fabric covering, of material such as flannel cloth, being provided therefor, the character of this covering being such as to readily permit passage of the gas to be purified therethrough, but to retain the purifying material in place. The inner perforated member 157, has cooperating therewith a layer, or stocking, of fabric or filamentous material 160, which, as described above, is preferably wool cloth or flannel. The members 156, 157 and 159 are so proportioned that a space of suitable dimensions is provided between them to receive the purifying material which is the same as that described above.

By means of this construction renewal of the purifying material is a comparatively simple matter. In order to renew this material the top 151 is removed, and the members 156, 157 and 159, which, for purposes of convenience in description are designated as a "cartridge" for receiving the purifying material, are removed as a unit. This cartridge, being removed, is inverted and the fouled purifying material dumped therefrom after which it is filled with new material and re-

placed in the purifier shell. The conical shaped end 154 of the outlet pipe and the hole or passage 155 have their cooperating surfaces finished to form a ground joint so that leakage therethrough is prevented. A bail or handle 161 is carried by the cartridge to facilitate its removal from, or insertion into, the shell 150.

The top 151 functions, not only as a covering to close the upper end of the purifier shell 150 but also as a saturator. This top is double walled, as is the case with the purifier described above in connection with Figs. 1 and 2, to provide a water receiving space 162. Depending from the top is a double walled flange 163, which, when the top is in position, extends downwardly into the purifier shell, being positioned between the upper end of the cartridge and the shell 150, and suitably spaced from each of these. This depending flange acts as a baffle to prevent the hot incoming gases from impinging directly upon the cartridge, and also, because of its construction, the heat transfer from the gases to the water within the vaporizing chamber 162, of which the space within the depending flange constitutes a part, is facilitated. An outwardly projecting flange or baffle member 164 which is attached to the lower end of the member 163, extends part way around the purifier shell, and functions to cause all of the incoming gases introduced through the pipe 68' to pass between the member 163 and the shell 150 and then to pass through an opening 165, as they travel through the purifier. These hot gases are thus caused to pass completely around the depending flange 163 thus increasing the time during which they contact with that member and thereby increasing the quantity of heat transferred to the water within the vaporizing chamber.

Water is introduced into the vaporizing chamber 162 by means of apparatus similar in principle, and quite similar in construction, to that described above. Associated with the member 151 is an open topped vessel 166, the interior of which is connected to the space 162. This member is preferably supported upon a pipe 167, one end of which is threaded within an outlet port in the member 166 and the other within an inlet passage, which opens into the space 162. Supported in any suitable manner, with its lower open end positioned within the vessel 166 is a bottle or vessel 120', which contains, during operation of the device, a reserve supply of water, to be admitted into the vaporizing chamber 162 as needed. As shown this bottle is supported by means of a standard 169, carrying suitable supporting rings 170, this standard being substantially identical in construction with supporting members of this kind which are in quite general use in chemical and physical laboratories. Any other desired means of supporting this bottle, such for ex-

ample as a standard carried by the shell of the purifier, may be used. The bottle is so positioned that the lower edge of its mouth corresponds with the desired level of water within the space 162, the level of the water within this space being thus automatically controlled. Air enters through the port 171, within the top 172 of the saturator, passing over the surface of the water within the space 162 and thence through the pipe 119' to the blast inlet 60', absorbing moisture as it goes. In order to increase the time during which the air is within the vaporizer, to thus insure its taking up the desired quantity of moisture, the baffle members 173 are provided so that the air takes a circuitous path. The top 172 is preferably made as a separate member of the saturator, to permit ready access to the vaporizer chamber.

In Figs. 6 and 7 is shown still another modified form of apparatus. In this modification the shell 20'', with the top and associated parts carried thereby, is substantially identical with the shell heretofore described in connection with Figs. 1 and 2. The base member 22'' is however materially different in that it is constructed to house the saturator or vaporizer. This base member is provided with a centrally arranged opening 40'' communicating with the ash pit 200, which ash pit with its door is substantially the same as the ash pit heretofore described in connection with the other modifications. Surrounding the ash pit, the base member is provided with two chambers 201 and 202, separated by the partition 203, neither of these chambers being in communication with the other, and the chamber 201 not being in communication with the ash pit. The chamber 201 is connected by means of the passage 67'', and through the pipe 66'' to the centrally arranged draft tube 65'', this chamber also being connected to one end of the pipe 68'' the other end of which opens into the purifier or separator. The chamber 202 is provided with a small well 204, see Fig. 8, to which is connected the pipe 205, the other end of this pipe opening into the vessel 206 of the water feed, this water feed being of the same general character as described above. A supporting flange 207 is associated with the vessel 206, the construction being such that a bottle or vessel 208 containing the main supply of water may be placed in inverted position, with its open end within the vessel 206 and at a height corresponding to the desired level of the water within the vaporizer chamber 202. Air passes into the vaporizer through a passage 209 in the outer wall thereof, shown in Fig. 12 and in dotted lines in Figs. 6 and 7, and thence into the ash pit through the passage 210 in the wall of the ash pit; shown in Fig. 13 and in dotted lines in Fig. 7, whence it passes upwardly through the tuyère 42'' within the refractory 130

ring 41", positioned within the opening 40", taking up moisture as it passes over the surface of the water within the vaporizer chamber. The offcoming gases pass through the chamber 201 on the way to the purifier and delivery main and heat the partition 203, which in turn heats the water within the chamber 202.

The grate for supporting the active fuel bed is quite different, in this modification, from the grate as above described. With any producer it is of course necessary that the ashes be removed from time to time. Otherwise these ashes will tend to accumulate and interfere with satisfactory operation. As illustrated herein, when a chemically active lining, such as a layer of the fuel being utilized in the gas generation, is used the path of the blast through the fuel bed and consequently the quantity of fuel within the active or ignited zone of the fuel bed is unimpeded. Of course where the conventional type of lining such as the ordinary firebrick lining is used, which lining is chemically inert, so far as the gas making reactions are concerned, and does not react chemically to assist in any way in the gas generation, the active or ignited zone of the fuel bed is positively defined and cannot possibly spread horizontally, or transversely, through the producer beyond the surface of this firebrick lining. But where no chemically inert lining of this character is used, but instead a chemically active lining is present, the unlined shell of the producer being filled with the fuel and the active or ignited zone controlled by the proportioning and positioning of the offtake relative to the tuyère, the blast is comparatively free, and will take the path of least resistance. If the quantity of blast in passing through the fuel bed increases the active zone will ordinarily be greater, transversely, than when a smaller amount of blast is utilized, it being, of course, obvious that with the central offtake fixed the maximum depth of the active fuel bed is constant and any variation in the quantity of the fuel within the active zone may occur only through the active zone spreading out radially. Consequently the active zone will, during operation, normally be of greatest diameter about midway between the tuyère and the draft tube. As shown in several of the figures this central part of the active zone is considerably greater in diameter than the tuyère opening and overhangs the refractory ring 41. Consequently ashes will tend to accumulate upon and around this refractory ring. In the type of base and grate construction shown in Figs. 1-5 these ashes will ordinarily be removed only when the producer is shut down and given a general cleaning out. Where the operation of the producer is not continuous, no trouble results from this accumulation of ashes, for

the producer will normally operate a number of hours without such an accumulation becoming troublesome. For example, where the producer is utilized for operating a conventional house lighting plant it will not ordinarily be subjected to a continuous run of more than 5 or 6 hours and there should normally be no trouble resulting from ash accumulation during such a period of operation. But if the producer should be used continuously, for a number of days, as would be the case where it generated gas for domestic use, such as cooking, heating, lighting, etc., this accumulation after several days' run might be sufficient to seriously interfere with the efficient operation of the producer. And the grate construction shown in Fig. 6 is especially designed for taking care of this condition.

The grate 211 is positioned above the tuyère or opening 42" instead of below it. Being so positioned it cannot be removed, as can the types of grates described above, in order to remove ashes accumulating thereon and on the base member and refractory ring. Therefore the grate is so constructed that ashes which tend to accumulate around it may be moved toward the periphery thereof and then into the ash pit, through the tuyère. While a number of different forms of grate have been found to function in a desirable manner for this purpose, that shown in the drawing is very satisfactory in operation. This grate is substantially hemispherical in form and is provided with suitable perforations 212 through which ashes fall into the ash pit. The grate is mounted upon a rotatable shaft 213 which extends downwardly through the bottom of the ash pit, being supported in a sleeve 214, threadedly mounted in the bottom of the ash pit, which sleeve also makes a tight joint to prevent the leakage of air into the ash pit. Rotatably mounted upon the lower end of the shaft 213 is an operating handle 215, the hub 216 of which is provided with a pawl or tooth 217, cooperating with the ratchet or teeth upon the sleeve 218, keyed to the shaft 213 so as to be slidable along that shaft but constrained to rotate with it. A spring 219 surrounds the shaft 213 one end bearing against the sleeve 214 and the other against the sleeve 218 to urge the member 218 into engagement with the hub 216. Proper actuation of the handle 215, will, through the ratchet and pawl mechanism described, give corresponding rotation of the grate 211. Such rotation will not only cause ashes to pass downwardly through the perforations therein but will also cause the ashes which do not pass therethrough to move toward the edge of the grate. In order to prevent the accumulation of ashes around the grate and tuyère opening, upon the ring 41", the grate is provided with a plurality of outstanding curved arms or scrapers 220, which are so arranged that as the grate

rotates they force the ash across the refractory ring 41" and cause it to pass through the opening therein into the ash pit.

This method of supporting the grate minimizes heat transfer therefrom into the shell and base of the producer and thus cuts down the transfer of heat from the active zone of the fuel bed into the surrounding atmosphere. But in this construction the transfer of heat into the base member, either through the grate or through the refractory ring 41" is of less importance than in the forms of construction described above. For most of the heat thus transferred to the base member seems to heat the walls of the vaporizer and walls therein to thus preheat the air, or blast, as it passes to the generator, and is thus carried back into the reaction zone.

As shown the base member is made in two pieces, the upper of which functions primarily as a base for the shell 20", the other containing the two chambers 201, 202, and the ash pit. The surfaces of these two members which cooperate when the device is assembled are properly machined to constitute ground joints, the ring 221 also being provided within the passage 67" to prevent the possibility of leakage through the joint at that place. In order to hold the two parts of the base member together, and at the same time hold the shell 20" tightly upon the packing positioned between it and the base member the lower section of the base member is provided with lugs having passages therethrough which cooperate with threaded passages in the upper section of the base. Bolts 222 are positioned within these passages and, when drawn tight, hold the two sections of the base together. Attached to the shell 20", near the bottom thereof, is a plurality of bolts or extensions 223, which, when the device is in assembled position are adapted to extend through passages 224 in the upper section of the base member. The free ends of these members 223 are threaded to receive supporting legs, such as described above, which, when they are tightened draw the composite base member, as a unit, tightly against the flange 32" of the shell.

The purifier shown in Fig. 6 is quite similar to that shown in Fig. 1, and described above. However, because of the vaporizer being positioned within the base member of the producer, that part of the construction shown in Fig. 1 is omitted. The purifying material used, in each of these purifiers, consists of very finely pulverized material, preferably such carbonaceous material as is used in the producer itself. The fuel used in the producer may be of widely varying character, but preferably charcoal, coke or anthracite coal is used, since the quantity of tar formed when gas is generated from these fuels is much less than where bituminous coal or lignite is used. While the producer

shown is fully adapted for the use of practically any carbonaceous fuel, the types of purifiers shown herein are primarily adapted for the cleaning of gases resulting from the gasification of charcoal, coke, anthracite coal or analogous fuels. These purifiers will function with gas generated from other fuels, but where the gas contains large quantities of tar, a purifier such as that shown in the patent to Harry F. Smith No. 1,099,773 will probably function more satisfactorily than the purifiers shown and described herein. Where large quantities of tar are present the purifiers described herein tend to clog up making necessary comparatively frequent renewal of the layer of purifying material. Where a fuel such as charcoal, for example, is used the impurities are deposited upon the layer of purifying material, forming a gummy layer upon the surface thereof. This deposited layer consists of a mixture of finely pulverized fuel, which is introduced, to a greater or less extent, into the generating chamber along with the fuel charged therein, in admixture with tar. If this layer of deposited material is removed, the original purifying material will be found unimpaired in effectiveness. In order to accomplish the removal of this layer without the necessity of closing down the plant and opening the purifier housing, a scraper member 230 is provided which is mounted upon the rotatable shaft 231, extending through the top 232, of the purifier, the outer end of this shaft being provided with an operating handle, or with wrench receiving surfaces to permit of rotation thereof. The purifier is preferably constructed of thin sheet metal. In order to give sufficient rigidity, and to provide a suitable bearing surface for the shaft 231 the two part sleeve and bearing 233 is provided, which serves also to prevent leakage along the shaft 231. As shown clearly in Fig. 11 the scraper member is curved so that upon rotation thereof it will force the deposited material across the layer of purifying material and over the edge thereof. During operation of the device it is sometimes found that the layer of purifying material settles so that although impurities are deposited upon the upper surface thereof the scraper is ineffective to remove them. The scraper member, is, therefore, provided with a plurality of teeth which break up this layer of deposited material as the scraper is rotated. If desired the scraper member may be entirely dispensed with and a rake member alone be utilized, the purpose of which is to break up this layer of deposited impurity. Preferably, however, the two are combined as shown in Figs. 6 and 11 so that not only is the layer of deposited material broken up, but it is also removed. As shown the combined rake and scraper member consists of a curved strip of material 234 to which is

- attached, by means of wood screws or in some other suitable way, strips of wood, designated generally by the numeral 235, through which project nails or wires 236 which extend down into the layer of purifying material. In order to insure a substantially uniform depositing of the impurities within the purifier, and to thus maintain the entire layer of purifying material of substantially uniform resistance to flow therethrough, baffles are provided which tend to cause the gas to so circulate within the purifier housing as to deposit the impurities uniformly over the entire surface of the layer of purifying material. As shown most clearly in Fig. 11 three of these baffles are provided, one designated by the numeral 237 extending across the far side of the purifier housing and at substantially right angles to the direction of flow of the gas as it passes from the pipe 68", the other two, designated generally by the numeral 238, also being arranged at substantially right angles to the direction of the flow of the gas but positioned across the near side of the purifier housing, and spaced apart so that most of the gas passing into the housing will flow between them, a small part of this gas being stripped off and caused to eddy between these baffles and the wall of the purifier. In its other details of construction this type of purifier is substantially identical with that shown in Fig. 1. Where this type of purifier is used the fuel introduced into the generating chamber of the producer need not be so carefully screened, to remove finely divided fuel, as is the case in the types of purifiers illustrated in Figs. 1 through 5. In fact substantial quantities of finely divided material may be purposely introduced into the generating chamber along with the fuel, so that the layer of deposited impurities will contain, proportionately, considerable quantities of solid fuel. The resulting deposited layer will consequently be less sticky and gummy, and may be more easily removed.
- In Figs. 9 and 10 is shown another type of grate adapted to facilitate the removal of ashes, as does the grate shown in Figs. 5 and 6. In this type of construction the grate proper, 250, has attached thereto, but suitably spaced therefrom a scraper member 251, this scraper member having an extension 252 attached at one side thereof, the free end of this member 252 being pivotally attached to the base member as shown at 253, so that the grate may be swung back and forth across the tuyère opening, and the refractory ring, to cause ashes to pass through this opening. For operating the grate an operating handle 254 is provided, one end of which is rigidly connected to the shaft 255 which extends upwardly through the base member of the producer. Rigidly mounted upon the inner end of this shaft is an arm 256, one end of which

is connected to one end of the link member 257, the other end of this link member being attached to the scraper element 251 of the grate. Movement of the handle 254, to rotate the shaft 255 will cause the grate, and associated scraper member to move back and forth thus forcing ashes out through the tuyère opening.

The gas producers illustrated are of comparatively small capacity, having a grate diameter of not more than twelve inches and preferably not more than six inches. But this invention is fully applicable to large size producers as well.

For any given fuel there is a certain effective thickness for the active zone which should be maintained in order to secure the most efficient gas generation. This most effective depth is apparently independent of the grate area. That is, by way of illustration, in small size producers, having a grate diameter of six inches, say, the effective depth should be from twelve to fourteen inches, where charcoal is used as a fuel. And this same effective depth should be maintained in larger size producers, those, say, having grate diameter of five or six feet, or more. This effective depth is controlled, in small size producers, by positioning the central off-take a suitable distance from the tuyère or grate. And the same method of controlling the effective depth may be used in larger size producers.

With a producer of the construction described, in which the conventional lining is dispensed with and a portion of the fuel bed itself functions as the heat insulating material, not only is the manufacture of the producer itself greatly simplified, and cost and trouble of maintenance greatly decreased, but in addition the gas making is more efficiently effected and the quality of the gas is also improved. Where a conventional lining is provided, which lining for purposes of description is designated as "chemically inert", the hottest zone in the fuel bed is normally adjacent the lining. This is due to the fact that resistance to flow of the blast through the fuel bed is less in this zone than in the center. Consequently not only is the gas generated in this outer zone of poorer quality than that generated in the center of the fuel bed, but, in addition, the temperatures are such that fusing of the ash, and even of the lining itself, may result, with the formation of clinkers. But where a portion of the fuel bed functions as a lining, which condition of operation is designated, for purposes of description, as having a "chemically active lining", that portion of the blast passing through the outer part of the active zone of fuel travels a greater distance than that portion passing through the center of the active portion of the fuel bed and therefore good gas results in this outer part, and at the

same time the temperature is not excessive. In addition, whereas a chemically inert lining is of such character that it will frequently react chemically with the ash at the high 5 temperatures attained to cause slagging or fusing, with resulting excessive formation of clinker, where the fuel itself acts as the lining this clinker trouble is obviated. For not only is carbon of such character that no fusing 10 temperature thereof is attained, but in addition it is chemically of such character that it will not react with the ash, or any of the other substances present in the fuel and in the ash to an appreciable extent, to 15 cause fusing. Thus not only is ordinary clinkering eliminated but in addition slagging of the lining is also prevented. Of course, if sufficiently high temperatures are attained there will be a fusing of the ash in 20 a producer having a chemically active lining, but inasmuch as there is nothing for the clinker to adhere to, no fixed lining to which it may become attached, any clinker which may be formed will pass downwardly as the 25 fuel is consumed and may be easily removed through the grate. Furthermore a lining of this character is continuously renewed, so that there is no necessity for shutting down the plant to repair the lining.

30 Not only is this type of producer construction advantageous, for the reasons set out above, but in addition it is, as stated above, especially advantageous in shortening the blowing up period. This is due partly to the 35 thorough heat insulation which exists. For crushed carbon is an almost perfect heat insulator, and in actual practice producers have been operated over long periods, with carbon lining, without the metallic shell becoming 40 sufficiently warm to be unpleasant to the touch. In addition this arrangement is such that whatever course the blast may take it is always in contact with chemically active material. Therefore, the active zone of the 45 fuel bed may fluctuate in extent without restriction, so that good gas will be generated without the entire fuel bed being brought up to a state of incandescence. That is, the range of load over which good gas will be 50 generated is wider than in the conventional producer. In effect, there is a producer of small diameter when the load is light and a producer of greater diameter when the load is heavier.

55 Of course, if desired, a lining of a definite form and thickness may be utilized. Such a lining is shown in Fig. 17, the lining being made up of carbon brick 275, instead of the conventional firebrick. Such a lining will 60 function satisfactorily, but it is of course open to the objection that renewal thereof is necessary if the brick are consumed so as to unduly decrease the thickness of the layer of insulating material. However, in the making 65 of such brick, carbon like that used in

carbon for arc lights is used and carbon of this character is greatly resistant to oxidation, even at very high temperatures. But if desired the diameter of the space within this lining, and the effective diameter of the grate, 70 may be greater than the normal width of the active zone of the fuel bed, and if thus proportioned renewal of such a lining should not be necessary, since the active zone of the fuel bed need not necessarily be so extensive as 75 to result in the carbon brick being consumed.

In the types of producers, described above, each producer is shown provided with a cover or closure member for the fuel supply opening. This construction is used where the 80 producer is designed primarily for a definite period of operation on one charge. In operating a conventional house lighting plant, for example, the producer will normally run about five or six hours to charge the batteries 85 of the plant. The producer shell is, therefore, made of such proportions that when fully charged it contains sufficient fuel to furnish gas for operating the Delco light engine over such a period of time. Where 90 the producer is so constructed it must be shut down in order to replenish the fuel supply, for the producer cannot operate with the fuel supply opening uncovered.

Where the gas plant is to operate continuously, as it would when supplying gas for domestic use, such as cooking, heating, lighting and the like, it is preferably provided with a fuel feeding mechanism so that fuel may be introduced into the producer, as 100 needed, without any interruption in the gas making reactions. A type of fuel feed, designed for this purpose, is shown in Figs. 14 and 15.

This fuel feed comprises a housing member 105 280, having a hollow cylindrical member 281, therein, a port 282 being provided in this hollow member. The member 281 is rotatably mounted, the construction being such that when in one position the port 282 therein will 110 be in full register with the inlet passage 283, of the housing 280, and when in a position 180 degrees therefrom, it will be in full register with the fuel discharge passage 284, within the housing 280. In feeding fuel to 115 the producer the rotatable member 281 is positioned with the pocket 282 in register with the passage 283. Fuel is then introduced to fill the interior of the member 281 after 120 which it is turned to bring the port 282 there-in into register with the fuel discharge opening 284. When the port 282 is in register with either of the passages 283 and 284 the other passage is closed off by the opposing wall of the cylindrical member 281. The escape 125 of gas or leakage of air through the fuel feeding mechanism is thus prevented, since the interior of the generating chamber is at no time in open communication with the atmosphere.

As shown, particularly in Fig. 15, the cylindrical member 281 is provided with end plates 285, attached thereto by means of bolts, each end plate being of such dimensions that it overlaps the cooperating end of the housing 280 to both retain the member 281 in position and tend to prevent the escape of gas or leakage of air at this point. For rotating the fuel feeding member 281 an operating handle 286, carried by a plate 287, attached to one of the end plates 285 is provided.

If desired a funnel 288, adapted to facilitate introduction of fuel into the passage 283, may be used.

15 This fuel feeding member is so designed that it is interchangeable with the closure member described above. The base of the housing 280 is provided with a groove 290, adapted to receive the upstanding flange 25, 20 surrounding the fuel inlet opening, suitable packing 291 being positioned therein to prevent leakage. The locking members 28, are so constructed that not only have they small lugs for receiving the bail which holds the 25 closure or cover in place, but also so constructed that they will cooperate with a flange 292, carried upon the base of the member 280 to hold that member tightly in engagement with the upstanding flange 25.

30 By means of this construction the fuel feeding member and the cover are made interchangeable, so that the same type of producer construction may be used where the gas making plant is to be used in connection with 35 a conventional house lighting plant, or where it is to be used for continuous operation generally. Or if desired both a cover and a fuel feeding mechanism may be provided and that one used which fits the needs of the particular occasion.

40 In Fig. 16 is shown a plan view of the locking member 28, this view with the sectional view shown in the various other figures furnishing a clear disclosure of the precise construction of this particular part of the apparatus.

While the method herein described, and the forms of apparatus for carrying this method into effect, constitute preferred embodiments 50 of the invention, it is to be understood that the invention is not limited to this precise method and forms of apparatus, and that changes may be made in either without departing from the scope of the invention which 55 is defined in the appended claims.

What is claimed is:

1. A gas producer comprising a gas generating chamber adapted to contain a fuel bed; a base member closing the lower end 60 thereof for supporting the fuel bed, said base member having an ash pit therein and a centrally arranged blast inlet opening therein connecting the generating chamber to the ash pit; and a grate coaxing with said opening 65 having a member for effecting movement of

ash from off the base member through the said blast opening into the ash pit.

2. In a gas producer system, a gas generator comprising a shell adapted to contain a fuel bed of solid carbonaceous material; a base member closing the lower end of said shell and having an ash-pit therein and an opening connecting said ash-pit to the interior of the generator, a refractory member within said opening, said refractory member having an opening therein centrally arranged with respect to the generator shell, and a grate cooperating with said last-named opening.

3. A gas producer comprising a shell adapted to receive a fuel bed; a base member closing said shell and having an ash pit therein and a blast opening connecting the ash pit and interior of the shell and of less diameter than the interior of said shell; a grate member positioned within said opening to support that part of the fuel bed thereover, the incandescent zone of the fuel bed during gas-making operation being of greater diameter than the said opening and the grate positioned therein and overhanging said opening and grate, whereby ashes tend to accumulate on the base member surrounding said blast opening, and a scraper extending over said base member for moving such accumulated ash across the said base member and through the said blast opening into the ash pit.

4. A gas producer comprising a gas generating chamber adapted to contain a fuel bed; a base member closing the lower end thereof for supporting the fuel bed, said base containing an ash pit and having a centrally arranged blast opening therein connecting the generating chamber to the ash pit; a grate rotatably mounted within said opening, and a scraper member carried by said grate and overlying the base member, adapted upon rotation of the grate to move ash from the base member through the centrally arranged blast opening into the ash pit.

5. In a gas producer system, a gas generating chamber comprising an unlined shell adapted to contain a fuel bed of solid carbonaceous material; a gas offtake positioned within the interior of said shell and adapted to be surrounded by fuel during operation; and blast means laterally spaced from the shell adapted to introduce a blast over a restricted portion of the fuel bed; the draft tube and the blast means being arranged close to each other so that the path of travel of the blast through the fuel bed will be so restricted that during gas-making operations the active zone of the fuel bed will not come into contact with the shell of the generating chamber.

6. In a gas producer system, a gas generator comprising an unlined shell adapted to contain a fuel bed of solid carbonaceous material; a centrally arranged draft tube serving as an offtake for the generated gas,

and means for introducing the blast for causing the gas-making reactions over a limited centrally arranged portion of the fuel bed, the blast introducing means and the blast tube being spaced substantially 12 inches apart.

7. In a gas producer system, a gas generator comprising a shell adapted to contain a fuel bed of solid carbonaceous material; a base member closing the lower end of said shell and having an ash-pit therein and an opening connecting said ash-pit to the interior of the generator, a refractory member supported within said opening, and spaced from the walls thereof to permit expansion and contraction, said refractory member being composed of heat insulating material and having an opening therein centrally arranged with respect to the generator shell, heat insulating material loosely arranged between the refractory member and the wall of the opening within which it is supported, this material being of such character as to permit ready expansion or contraction of the refractory member, and a grate cooperating with said last-named opening.

8. A gas producer comprising a manually portable unlined shell of sheet metal adapted to contain a fuel bed; a base member for closing the lower end of said shell, and supporting the shell and fuel bed therein; and means for detachably connecting the shell and base member, whereby the shell may be temporarily disconnected from the base member for cleaning and the like.

9. A gas producer comprising a manually portable unlined shell adapted to contain a fuel bed; a base member closing the lower end of said shell and adapted to support the shell and fuel bed contained therein; packing material interposed between the shell and the base member to prevent leakage therebetween; and means for holding the shell and base member in detachable, but, rigid, connection, whereby the shell may be temporarily disconnected from the base member for cleaning and the like, and thereafter readily reconnected in gas-tight connection.

10. A gas producer comprising a manually portable shell adapted to contain a fuel bed; a base member closing the lower end of said shell and adapted to support the shell and the fuel bed contained therein; packing material interposed between the shell and the base member to prevent leakage therebetween and means for holding the shell and base member in detachable, but rigid, connection, said means comprising threaded extensions rigidly attached to the shell, cooperating passages in the base member through which said threaded extensions extend when the shell and base member are in assembled position, and supporting legs for said base member, each of said legs having a threaded socket to receive the said threaded extensions, whereby

when the legs are screwed tight on the extensions, the base member and shell are held rigidly in assembled position.

11. A gas producer comprising a gas generating chamber adapted to contain a fuel bed; a base member for closing the lower end of said generating chamber having a centrally arranged blast opening therein; a rotatable grate cooperating with said blast opening, the grate and base member serving to support the fuel bed within the generating chamber, scraper means attached to said grate, adapted upon rotary movement of the grate to move ash toward the center of the producer and cause the ash to pass through said blast opening; and means for rotating said grate, said means being operable from outside the producer.

12. A gas producer comprising a gas generating chamber adapted to contain a fuel bed; a base member for closing the lower end of said generating chamber and having a centrally arranged blast opening; a rotatable grate cooperating with said blast opening, the grate and base member serving to directly support the fuel bed within the generating chamber, scraper means attached to said grate adapted upon rotary movement of the grate to move ash toward the center of the producer and cause the ash to pass through said blast opening; and means for rotating said grate, said means being operable from outside the producer, and comprising a ratchet and pawl arrangement.

13. In a gas producer system, a gas generator comprising a shell adapted to contain a fuel bed of carbonaceous material; a base member closing the lower end of said shell and having a blast opening therein, a grate within said blast opening, the grate and base member serving to support the fuel bed in the generating chamber; means for introducing a blast of air and moisture into the fuel bed to cause the generation of combustible gas; and means including a solid heat-insulating material between said base member and the active zone of the fuel bed for heat insulating the active zone of said fuel bed from the said base member to confine the heat within said active zone.

14. A gas producer comprising a shell adapted to contain a fuel bed; a base member, closing the lower end of said shell and adapted to support the fuel bed within said generator, said base member having a blast opening therein for the introduction of the gas making blast into the fuel bed, and a separate gas offtake in said base member through which the generated gas resulting from the blasting of the fuel bed through said blast opening passes off from the generating chamber in heat-transferring relation with said gas-making blast.

15. A gas producer comprising a gas generating chamber, adapted to contain a fuel bed;

- a base member closing the lower end of said generating chamber and adapted to support the fuel bed within said generating chamber, and having a blast opening therein through which air and moisture is introduced into the fuel bed for causing the generation of combustible gas, said blast member having a gas offtake passage therein connecting the interior of the generating chamber to the gas delivery main; and a saturator within said base member, in heat transferring relation with said gas offtake passage, said saturator having an air inlet opening connecting the interior of said saturator with the atmosphere, and an outlet opening connecting the interior of said saturator to the said blast opening.
16. In a gas producer comprising a gas generating chamber adapted to contain a fuel bed, said generating chamber having an inlet through which a blast is introduced into the fuel bed to cause the generation of combustible gas, and an offtake through which the hot generated gases pass off from the generating chamber; a saturator, comprising a vaporizer chamber for containing a quantity of water, positioned in heat transferring relation with said gas offtake, whereby the water within said vaporizer chamber is heated by the hot offgoing gases, means connecting the vaporizer chamber of the saturator to the atmosphere, other means connecting the interior of said chamber to the blast inlet; and means for supplying water to said chamber to maintain the water level therein substantially constant, said means comprising an inverted vessel for containing water to be supplied to the saturator, and means for maintaining said vessel in inverted position with the discharge orifice positioned at a predetermined level, whereby the level of water in the vaporizer will control the discharge of water from the vessel.
17. A gas producer comprising, in combination, a gas generating chamber adapted to contain a fuel bed; a base member therefor closing the lower end of the generating chamber and supporting the fuel bed, means connecting the generating chamber and base member; said base member having a blast opening therein, a central draft tube positioned within the generating chamber; an ash pit within the base member connected to the interior of the generating chamber by means of said blast opening; a saturator in the base member comprising a vaporizer chamber connected to the ash pit for supplying moisture to the blast; a gas offtake passage in the base member connected to the central draft tube and to a delivery main, and positioned in heat transferring relation with the saturator so that the hot gases passing off through said passage will heat the water in the vaporizer chamber; and means cooperating with said saturator for maintaining a constant level of water in said vaporizer chamber.
18. A gas producer comprising, in combination, a gas generating chamber adapted to contain a fuel bed; a base member therefor closing the lower end of the generating chamber and supporting the fuel bed, means detachably connecting the generating chamber and base member, said base member having a blast opening therein, a central draft tube positioned within the generating chamber; an ash pit within the base member connected to the generating chamber by means of the blast opening; a saturator in the base member comprising a vaporizer chamber connected to the ash pit and also to the atmosphere; a gas offtake passage in the base member connected to the central draft tube and to a delivery main, and positioned in heat transferring relation with the saturator so that the hot gases passing off through said passage will heat the water in the vaporizer chamber; and means cooperating with said saturator for maintaining a constant level of water in said vaporizer chamber, said means comprising an inverted vessel for containing water to be supplied to the saturator, and means for maintaining said vessel in inverted position with the discharge orifice positioned at a predetermined level, whereby the level of the vaporizer will control the discharge of water from the vessel.
19. A gas producer comprising, a shell adapted for containing a fuel bed, a base member closing the lower end of the shell, and supporting said shell and fuel bed therein, said base member consisting of an upper section and a lower section; the upper section of the base member having a blast opening therein; a centrally arranged ash pit in the said lower section, a horizontal partition separating said lower section into two horizontal chambers, one of which is adapted to contain a quantity of water and to function as a saturator chamber, said chamber, when the producer is assembled, being connected to the atmosphere, and to the ash pit, the ash pit in turn being so positioned as to connect with the blast opening in the upper section of the base member, the other chamber serving as a gas offtake passage, the gas as it passes therethrough, imparting heat to the water in the saturator chamber; detachable means for holding the two sections of the base member in gas tight connection; and detachable means for connecting the base member, as a whole, to the producer shell.
20. A gas producer comprising a gas generating chamber adapted to contain a fuel bed of solid carbonaceous material; means for supporting said fuel bed, having a blast opening therein, of substantially less diameter than the said generating chamber; and a draft tube positioned within said generating chamber and adapted to be surrounded by

- by fuel during operation, the draft tube and blast opening being so proportioned and positioned close to each other that the sash of the travel of the blast through the fuel bed
- 5 within said generating chamber during operation will be laterally restricted to limit the maximum extent of the active zone of said fuel bed so that such active zone will be during operation surrounded by a zone of inactive fuel.
- 10 21. In a gas producer, a gas generator comprising an unlined shell adapted to contain a fuel bed; a base member for supporting said fuel bed having a blast opening therein of substantially less diameter than the shell of the generator; a central draft tube within said generator and spaced from the said blast opening; the base member and central draft tube being relatively so arranged and positioned that the distance between the effective periphery of the central draft tube and the upper face of the base member increases from the immediate zone of the blast opening outwardly toward the shell.
- 15 22. A gas producer comprising a shell adapted to contain a fuel bed, a base member receiving the lower end of said shell and adapted to support the fuel bed, said base member having a blast opening therein through which a blast of air and water vapor is adapted to be introduced into the fuel bed for causing the generation of combustible gas, said base member also having a gas off-take passage therein through which said hot
- 20 30 35 40 45 50 55 60 65 generated gas is adapted to pass, said base member also having a saturator chamber therein positioned in heat-transferring relation with said gas-offtake passage, said saturator chamber being adapted to supply water vapor to said blast.
23. In a gas producer comprising a generating chamber adapted to contain a fuel bed, and means for flowing a blast of air and moisture through said fuel bed to cause the generation of combustible gas; a saturator located in heat-conducting connection with the blast inlet portion of said fuel bed, and means for removing from the fuel bed the gases generated therein and for passing said removed gases in heat-transferring contact with said saturator.
24. A gas producer comprising a body member containing a generating chamber adapted to contain a fuel bed; a base member closing the lower end of said body member, and supporting the body member and fuel bed therein, a saturator located in said base member in direct heat conducting relation with the lower part of said fuel bed, a gas offtake passage within the base member; and a gas offtake pipe connecting the interior of the generating chamber above the incandescent zone to the said gas offtake passage, whereby the saturator will receive heat on one side from the fuel bed resting upon the base
- member, and will receive heat on the other side from the heated generated gases as such gases pass through the said offtake passage in said base member.
- In testimony whereof I hereto affix my sig- 70 nature.
- HARRY F. SMITH.

CERTIFICATE OF CORRECTION.

Patent No. 1,772,642.

Granted August 12, 1930, to

HARRY F. SMITH.

It is hereby certified that error appears in the printed specification of the above numbered patent requiring correction as follows: Page 14, line 7, claim 15, for the word "blast" read base; page 15, line 3, claim 20, for "sash" read path; and that the said Letters Patent should be read with these corrections therein that the same may conform to the record of the case in the Patent Office.

Signed and sealed this 23rd day of September, A. D. 1930.

(Seal)
